RAILWAY TRACK CIRCUIT APPARATUS

Norman F. Agnew, Penn Township, Allegheny County, and Paul N. Martin, Wilkinsburg, Pa., assignors to The Union Switch & Signal Company, Swissvale, Pa., a corporation of Pennsylvania

Application July 31, 1941, Serial No. 404,823

5 Claims. (Cl. 175—320)

Our invention relates to railway track circuit apparatus, and it has particular reference to the organization of such apparatus into novel and improved railway track circuits. More particularly, our invention relates to railway track circuits incorporating apparatus arranged to be independent of variations in track ballast resistance.

Railway track circuits have been proposed heretofore incorporating relays arranged to effect operation of their contacts only in response to rapid changes in the track circuit energy received by the relays, as when a train enters or leaves a track circuit, but not in response to gradual changes in the relay energization effected due to changes in track ballast resistance caused by atmospheric conditions, etc. In such systems, the relays employed have been designed to adjust their release energy levels in accordance with existing ballast resistance conditions, while the pick-up energy levels of the relays are determined in accordance with the ballast conditions existing at the time the relays become released. When a train enters such a circuit adjusted for extremely dry (or high resistance) ballast, and during the occupancy of the circuit, the ballast resistance varies and becomes lower due, for example, to an extremely heavy rainfall, there is a possibility that the relay might not pick up, after the train vacates the circuit, because the increase in current leaking across the ballast might cause the energy available at the relay to decrease to a value insufficient to effect operation of the relay to its picked-up position.

In view of the above-mentioned and other important considerations, it is an object of our present invention to provide novel and improved railway track circuit apparatus arranged in such manner that not only the release but also the pick-up levels of the circuits are adjusted in accordance with existing track ballast conditions.

Another object is the provision, in a railway track circuit, of a relay incorporating means for adjusting its pick-up energy level in accordance with ballast conditions existing at the time the track circuit becomes vacated.

A further object is the provision of railway track circuits incorporating a relay arranged to respond only to rapid changes in energy received by the relay, and incorporating means for compensating for gradual changes in track ballast conditions when the circuit is occupied as well as when the circuit is unoccupied.

An additional object is the provision of rail-

way track circuit apparatus arranged in such manner that the release and pick-up values of the circuits are maintained substantially constant regardless of variations in track ballast resistance.

The above-mentioned and other important objects and characteristic features of our invention which will become readily apparent from the following description, are attained in accordance with our invention by incorporating into a track circuit a relay responsive only to sudden changes in the energy received by the relay and arranged to have both its release and pick-up values independent of variations in ballast resistance. The relay comprises a movable element which adjusts its position in accordance with the energy received by the relay from the track circuit, contact means operated by the movable element, and inertia means cooperating with the movable element for causing operation of the contact means in response to a sudden movement of the movable element occasioned by a train entering or leaving the track circuit, the inertia means being free to assume a biased position following a sudden movement of the movable element caused by the train entering the section, whereby to cause operation of the contact means, upon the following sudden movement of the movable element caused by the train vacating the section, to be independent of the track ballast resistance.

We shall describe several forms of track circuit apparatus embodying our invention, and shall then point out the novel features thereof in claims.

35 In the accompanying drawing, Fig. 1 is a diagrammatic view illustrating one form of apparatus embodying our invention. Figs. 2 and 3 are diagrammatic views each illustrating a modified form of the apparatus represented in Fig. 1, and each also embodying our invention. In each of the several views, similar reference characters have been employed to designate corresponding parts.

40 Referring to the drawing, the reference characters 1 and 1a designate the track rails of a stretch of railway track divided by insulated joints 2 into an insulated track section D—E. Section D—E is provided with a track circuit comprising a suitable source of energy, such as 45 a track battery 4, connected through a resistor 5 to the rails at one end E of the section, and a track relay TR connected across the rails at the other end of the section. Relay TR is of the type arranged to operate its contacts in response to 50 abrupt and relatively large changes in the ener-

gization of the relay windings but not in response to gradual changes in the relay energization. The relay may, for example, be of the galvanometer type or, as shown, relay TR may be of the tractive armature type.

Relay TR, as shown, comprises a magnetizable core 6 provided with an operating winding 7, another magnetizable core 8 provided with an auxiliary winding 9, and two movable armature members 10 and 11 provided for and disposed in the magnetic fields of windings 7 and 9, respectively. Armature 10 is pivoted at 12 and is biased, as by means of a spring 13, into engagement with a backstop 14. The armature is relatively light so that it has relatively little inertia, hence it responds readily to the flux created by current in winding 7, and is proportioned to assume different positions according to the energization of the winding. That is to say, when winding 7 is deenergized, armature 10 is released and rests against its backstop 14. When winding 7 is energized, armature 10 is attracted and moves against the action of spring 13 toward core 6 a distance dependent upon the energization of the winding. This characteristic of armature 10 may be effected by providing a relatively large air gap between armature 10 and core 6 and by properly proportioning spring 13.

The other armature 11 is pivoted at 15 and is biased, as by a spring 16, into engagement with stop 17. This armature is provided with a relatively heavy counterweight 18 and has a relatively large inertia, hence it has a relatively slow rate of movement. The armature is operated away from stop 17 and is normally positioned in accordance with the energization of winding 7, by means of an extension 19 secured to armature 10 and engaging extension 20 secured to armature 11. The extensions 19 and 20 when in engagement with each other form a circuit controlling contact which we shall designate as contact 19-20.

Armature 11 is arranged, however, so as at times to respond to flux due to current in winding 9 and occupy a position dependent upon the energization of the winding. The parts are so proportioned that armatures 10 and 11 are caused to assume corresponding positions when the same current is present in windings 7 and 9, and the armatures 10 and 11 are caused to move correspondingly when the current in the respective windings varies slowly. The stops 14 and 17 are positioned to limit movement of their respective armatures 10 and 11 so that when both windings 7 and 9 are deenergized, armature 10 drops away from core 6 a greater distance than armature 11 drops away from core 8, hence under such conditions contact 19-20 is opened.

Relay TR has associated therewith a repeater relay TP controlled over a circuit extending from terminal B of a suitable source of current, such as a battery not shown but having its opposite terminals designated by the reference characters B and C, through contact 19-20 of relay TR and the winding of relay TP to terminal C. Relay TP is provided with contact members, such as member 22, which may be utilized to control the usual functions, such for example as signals, locks, etc., usually controlled by track circuit apparatus, and also has a bifurcated contact member 23 which functions as a bridging member of a make-before-break or continuity transfer contact combination.

In the normal condition of the apparatus represented in Fig. 1, section D-E is unoccupied

and only winding 7 of relay TR is connected in circuit with the track rails. The energization of winding 7 causes its associated armature 10 to be operated against the action of spring 13 to a position dependent upon the energy received by the winding from the track rails, and under vacant conditions in the section, armature 10 is caused to move to a position wherein extension 19 engages extension 20 and operates armature 11 away from its stop 17 to a position which corresponds to the position of armature 10 and hence to the energization of winding 7. Contact 19-20 accordingly is closed, relay TP is energized and contact member 23 is in its upper or front position to close front contact 23-24 and thus connect winding 7 and resistor 26 across the rails of the section at end D over an obvious circuit.

If, now, a change occurs in the ballast conditions and there is a corresponding change in the energy at the relay end of the circuit available to energize relay TR, armature 10 will be caused to assume a different position to correspond to the new energy level in winding 7. For example, if the ballast becomes wet and less energy is available to energize winding 7, armature 10 will drop away from core 6 to a position where the torque exerted on the armature by spring 13 is just balanced by the torque on the armature due to the magnetic flux created by current in winding 7. In like fashion, should the ballast dry out and more energy become available for winding 7, then armature 10 assumes a position nearer core 6.

These variations in ballast conditions of course occur very gradually, hence the movement of armature 10 to or from its core 6 to the new position of correspondence with the energization of winding 7, occurs at a relatively slow rate within the rate of movement of armature 11. It follows, therefore, that each movement of armature 10 caused by a gradual change in energization of winding 7 effects a corresponding movement of armature 11, and the two armatures "float" up and down and assume positions corresponding to the energization available at the relay. Contact 19-20 of relay TR is thus caused to remain closed for gradual changes in energization of winding 7, and relay TP remains energized.

When, however, a sudden change is effected in the energization of winding 7, as when a train enters section D-E and the established train shunt lowers the voltage available at the relay end of the circuit, armature 10 quickly drops away from core 6, but due to the large inertia and slow rate of movement of armature 11, the latter armature slowly follows the movement of the first. Contact 19-20 is, therefore, opened immediately when section D-E becomes occupied, and relay TP releases. During the travel of contact member 23 from its front point 24 to its back point 25, contact 23 bridges both front and back points so that back contact 23-25 is closed prior to front contact 23-24 being opened. When back contact 23-25 closes, winding 9 is connected in series with winding 7 across the track rails. If, now, the train shunt is effective and of low resistance, the energization of both windings 7 and 9 may be reduced to a value insufficient to operate their respective armatures 10 and 11 away from their backstops 14 and 17, hence contact 19-20 remains open. However, should the train shunt be of high resistance, windings 7 and 9 may be energized sufficiently to operate their armatures away from their backstops. At this time both windings are energized

in series so that the current in the two windings has an equal value. The position assumed by armature 10 in response to the energization of winding 7 will thus correspond to the position assumed by armature 11 in response to the energization of winding 9, the armatures are caused to move corresponding distances without change in their relative positions upon a change in the energy level in the windings, and as a result contact 19-20 remains open.

Under the conditions just described, that is, with a train in section D-E and windings 7 and 9 sufficiently energized to cause operation of armatures 10 and 11 away from their backstops, the ballast conditions may vary and in turn vary the energization of windings 7 and 9. For example, if the train enters section D-E when the ballast is dry, and remains in the section during a rainfall, the resistance of the ballast would then gradually change from one of relatively high resistance to a lower resistance, hence under such conditions less energy would be available to energize windings 7 and 9 due to the increased leakage across the ballast. This change in energization of the windings would, of course, occur only gradually so that armatures 10 and 11 will be caused to move slowly to positions corresponding to the existing energization of the windings. The rate of this movement is within that of the relatively slow moving armature 11, with the result that both armatures move corresponding distances and do not change their relative positions, and hence contact 19-20 remains open. It follows, therefore, that armatures 10 and 11 "float" apart by moving up or down depending upon the energization of the windings as determined by the effectiveness of the train shunt and the ballast resistance.

When the train vacates section D-E, the energization of windings 7 and 9 rapidly increases and winding 10 is moved rapidly toward core 6. Armature 11 does not, of course, move as rapidly, hence contact 19-20 becomes closed. Relay TP, at the end of its relatively short delay interval, picks up to open its back contact 23-25 and closes its front contact 23-24, thereby opening the circuit of winding 9 and inserting resistor 26 in series with winding 7. Resistor 26 preferably has a resistance equal to that of winding 9 so that the energization of winding 7 is not altered. The apparatus is, therefore, restored to its normal condition wherein armature 10 assumes a position dependent upon the energization of winding 7, and armature 11 is likewise positioned in accordance with the energization of winding 7 due to contact member 19 engaging extension 20.

From the foregoing, it is readily apparent that track circuit apparatus embodying our invention is arranged so as to cause operation of its contacts only in response to sudden changes in energy available at the track relay but not in response to gradual changes, and also that the relay is arranged to adjust both its release and its pick-up energy levels to ballast conditions. It is further apparent that if the relay is energized sufficiently to operate its armatures during the interval that the section is occupied, the armatures are caused to assume positions dependent upon either or both the effectiveness of the train shunt and the track ballast conditions. It follows that should the ballast conditions change during the period of occupancy of the section, the relay will pick up and cause operation of its contacts when the section becomes vacated.

In a second form of apparatus embodying our invention and represented in Fig. 2, we employ a relay TR1 having a sluggish or high inertia member 11, pivoted at 15, coupled by a spring 30 to armature 10 and by a spring 31 to armature 32 of relay TP. In the normal condition of the apparatus, as represented in the drawing, armature 10 assumes a position dependent upon the energization of winding 7, springs 30 and 31 act on member 11 to cause it to move to a position wherein extension 19 engages extension 20 to close contact 19-20, and relay TP is energized over its obvious circuit including contact 19-20 of relay TP. The parts are so proportioned that under vacant conditions in section D-E, armature 10 will move slowly should the energy level in winding 7 change slowly, and member 11 follows the slow movement of armature 10 to keep contact 19-20 closed.

When, however, the energy in winding 7 decreases suddenly due to a train entering the section, armature 10 drops away from core 6 to its stop 14, extension 19 drops away from extension 20 and breaks contact 19-20, and relay TP releases its armature 32 to release the tension in spring 31. Pack contact 34 of relay TP also closes to provide a shunt path around resistor 33 interposed in circuit with winding 7 of relay TR1. The springs 30 and 31 are so selected that with armature 10 against its backstop 14, the torque exerted by spring 30 on member 11 causes it to operate slowly and move to a position in engagement with its backstop 17, the backstops 14 and 17 being so located that when members 10 and 11 rest upon their respective stops, contact 19-20 is opened. This condition of the apparatus is maintained until section D-E becomes vacated, whereupon the energy in winding 7 increases rapidly and armature 10 is operated toward core 6. Extension 19 accordingly engages extension 20 to close contact 19-20, relay TP is energized and picks up its armature 32 to increase the tension in spring 31 to compensate for the now lessened tension in spring 30, and back contact 34 of relay TP opens to insert resistor 33 in circuit with winding 7. The apparatus accordingly is restored to its normal condition as represented in the drawing.

Relay TR2, represented in Fig. 3, differs from relay TR1 in that movable member 11 is supported on a knife-edged bearing member 40; a compression spring 41 disposed between extensions 19 and 20 biases the extensions apart, but the two extensions normally are in engagement and contact 19-20 is closed, due to the action of tension spring 31 connected to member 11 and armature 32 of relay TP, and the gravity bias of member 11, which tends to rotate member 11 in a counterclockwise direction (as viewed in Fig. 3). Armature 10 of relay TR2 is arranged, as pointed out heretofore, to adjust its position with respect to the energization of winding 7, and for relatively slow movements of armature 10, corresponding movements of armature 11 are effected so that the relative positions of the members remain the same and contact 19-20 is closed. When the energization in winding 7 suddenly decreases, armature 10 drops, contact 19-20 opens to deenergize relay TP, and member 11 slowly operates toward its stop 17. Armature 10 and member 11 normally continue to rest against their respective stops, but should the train shunt be of relatively high resistance, armature 10 might be operated by winding 7 away from stop 14. The springs 31 and 41 are selected so

that if relay TP is released, the spring 41 is effective when armature 10 moves slowly, to keep armature 10 and member 11 separated sufficiently to maintain open contact 19-20, but when armature 10 moves rapidly, as in response to the sudden increase in energy in winding 7 due to the train vacating section D-E, then the inertia of member 11 prevents rapid movement of the member and enables armature 10 to compress spring 41 sufficiently to bring extension 19 into engagement with extension 20, thereby closing contact 19-20 and energizing relay TP. When relay TP picks up, spring 31 is made effective to exert upon armature 11 a torque sufficient to overcome the torque exerted on member 11 by spring 41 tending to separate member 11 from armature 10. The relay accordingly is restored to its normal condition wherein contact 19-20 is maintained closed during relatively slow movements of armature 10 to positions corresponding to the energy level in winding 7.

From the foregoing, it is readily apparent that we have provided novel and improved forms of railway track circuit apparatus arranged to operate its contacts only in response to abrupt changes in energy available but not to gradual changes, and which apparatus is arranged to adjust both its pick-up as well as the release values in accordance with ballast resistance variations. It follows, therefore, that should the ballast resistance change considerably during the interval that a track circuit is occupied, the apparatus will pick up upon the train vacating the section.

Although we have herein shown and described only a few forms of railway track circuit apparatus embodying our invention, it is understood that various changes and modifications may be made therein within the scope of the appended claims without departing from the spirit and scope of our invention.

Having thus described our invention, what we claim is:

1. A relay of the direct current tractive type for use with track circuits on railroads comprising, a winding, a first pivoted member disposed in the field of said winding, means operatively connected with said first pivoted member for adjusting it to assume different positions according to the energization of said winding, a second pivoted member biased into engagement with said first member and positioned in accordance with the position of the first member, said second member having a relatively slow rate of movement as compared to the first member whereby motion of the first member relative to the second is attained to effect separation or engagement of said members upon sudden decreases or increases respectively in energization of said winding but corresponding movements of both members without change in their relative positions are attained to maintain engagement of said members upon gradual changes in energization of said winding, means responsive to a sudden decrease in energization of said winding and resultant movement of said first member relative to, and away from, said second member, and means rendered effective by said last-mentioned means for effecting corresponding movements of said first and second members without change in their relative positions out of engagement with each other for gradual changes in the energization of said winding.

2. In combination with a magnetizable core provided with a winding and an armature pivoted for swinging movement toward and away from

said core, means cooperating with said armature for causing it to assume a position dependent upon the energization of said winding, a second magnetizable core provided with a second winding and a second armature pivoted for swinging movement toward and away from said second core, means cooperating with said second armature for causing it to assume a position dependent upon the energization of said second winding, the inertia of said second armature being relatively high with respect to the inertia of said first armature, a first member carried by said first armature and normally engaging a second member secured to said second armature to position the said second armature in accordance with the energization of said first winding, a relay provided with an energizing circuit completed when said first and second members are in engagement, circuit means controlled by a front contact of said relay for energizing said first winding but not said second winding, for causing corresponding movements of both said armatures without change in their relative positions upon slow changes in energization of said first winding and causing a movement of said first armature relative to said second armature to effect separation of said first and second members upon a rapid decrease in energization of said first winding, and circuit means controlled by a back contact of said relay for energizing both said windings in series, whereby to cause both windings to be effective to operate their respective armatures to obtain corresponding movements of both armatures without change in their relative positions upon slow changes in energization of said windings and effective upon a rapid increase in energization to cause said first armature to move relative to said second armature to a position wherein said first and second members are in engagement and complete the circuit means over which said relay is energized.

3. In combination with a magnetizable core provided with a winding and an armature pivoted for swinging movement toward and away from said core and arranged to assume a position dependent upon the energy level of said winding, a movable member pivoted for rotation and having a relatively high degree of inertia with respect to the inertia of said armature, a member secured to said armature for normally engaging said movable member to position the latter member in accordance with the energization of said winding, a relay energized over a circuit completed when said armature member and movable member are in engagement, a coupling between the armature of said relay and said movable member for urging said latter member into engagement with said armature member when said relay is energized, whereby to cause corresponding movements of said first armature and movable member without change in their relative positions upon slight and gradual changes in the energy level of said winding and effective upon a large and rapid change in energy level to cause movement of said first armature member with respect to said movable member.

4. In a relay, the combination of an electromagnet, a first armature member pivoted in the field of said electromagnet and biased away from said electromagnet, means cooperating with said first armature member for limiting its movement in response to its bias to a given position, means operatively connected with said first armature member for opposing the action of said electro-

magnet on said first armature member whereby to cause that member to adjust its position in said field in accordance with the energization of said electromagnet, a second pivoted member positioned to be supported by said first armature member and biased away from said electromagnet, means cooperating with said second pivoted member for limiting its movement in response to its bias to another position to which it is free to move when not supported by said first armature member and in which position said second pivoted member is out of engagement with said first armature member in its given position, and inertia means operatively connected with said second pivoted member and having a relatively low rate of movement with respect to the rate of movement of said first armature member whereby when said second pivoted member is supportingly engaged by said first armature member corresponding movements of both members without change in their relative positions are attained to maintain such members in engagement upon gradual changes in the energization of said electromagnet while motion of said first armature member relative to said second pivoted member is attained to effect the engagement or disengagement of such members when the energization of said electromagnet abruptly increases or decreases, respectively.

5. In combination, a first winding variably energized from a source of current, a first armature member pivoted in the field of said first winding and biased away from that winding, means cooperating with said first armature member for limiting its movement in response to its bias to a given position, means operatively connected with said first armature member for opposing the action on that member of said first winding whereby to cause that member to adjust its position in said field in accordance with the energization of said first winding, a second armature

member pivotally positioned to be supported by said first armature member and biased away from said first winding, means cooperating with said second armature member for limiting its movement in response to its bias to another position to which it is free to move when not supported by said first armature member and wherein it is out of engagement with that member in its given position, inertia means operatively connected with said second armature member and having a relatively low rate of movement with respect to the rate of said first armature member whereby when said first armature member supportingly engages said second armature member corresponding movements of both members are attained to maintain such members in engagement upon gradual changes in the current value in said first winding while motion of said first armature member relative to said second armature member is attained to effect the engagement or disengagement of such members when the energization of said first winding abruptly increases or decreases, respectively, a relay energized over a circuit including a contact closed when said first and second members are in engagement, a second winding disposed in magnetic relation to said second armature member, means operatively connected with said second armature member for opposing the action on that member of said second winding whereby to cause that member to adjust its position in accordance with the energization of said second winding, and an alternate circuit including a back contact of said relay for simultaneously energizing both said first and second windings from said source for at times causing said first and second members to position themselves in accordance with the current values in said first and second windings respectively.
